UNITED STATES PATENT OFFICE.

JAMES J. FITZGERALD, OF PITTSBURGH, PENNSYLVANIA.

GAME APPARATUS.

1,161,649.

Specification of Letters Patent.

Patented Nov. 23, 1915.

Application filed November 22, 1913. Serial No. 802,501.

To all whom it may concern:

- Be it known that I, JAMES J. FITZGERALD, a citizen of the United States of America, residing at Pittsburgh, in the county of 5 Allegheny and State of Pennsylvania, have invented certain new and useful Improvements in Game Apparatus, of which the following is a specification, reference being had therein to the accompanying drawing.
- 10 This invention relates to game apparatus, and has for its object to provide a device of such class, in a manner as hereinafter set forth for playing an unusually interesting and scientific game entitled Hydrero, due 15 to the fact that the game, when playing the same includes an attack from pieces or members having the representations of aerial, marine and sub-marine vessels and mines and a defense set up by pieces or members 20 having the representations of aerial, marine and sub-marine vessels and mines.
- 25 A further object of the invention is to provide a game apparatus including a playing field formed of a series of rows of equilateral triangular playing divisions over which are adapted to be moved or shifted two sets of playing pieces or members, the members of each set being suitably designated, each set containing an object piece 30 for the members of the other set to attack and take, the members of each set that are not similarly designated having different modes of move with respect to each other over the playing field.
- 35 With the foregoing and other objects in view, the invention consists of the novel construction, combination and arrangement of parts as hereinafter more specifically described and illustrated in the accompanying 40 drawings, wherein is shown an embodiment of the invention, but it is to be understood that changes, variations and modifications can be resorted to which come within the scope of the claims hereunto appended.
- 45 In the drawings wherein like reference characters denote corresponding parts throughout the several views: Figures 1 and 1^a when taken together illustrate a game board for a playing field in accordance with this invention and further having arranged thereon the playing pieces or members prior to the commencement of the game, Fig. 2 is a view illustrating a form of playing piece or member, Fig. 3 is a view of

an indicator piece, Figs. 4, 5, and 6 are 55 views of blocks representing respectively a fort, wireless station, wireless torpedo station.

Referring to the drawings in detail, A denotes a game board provided with rows of 60 equilateral triangular spaces and each row having alternate spaces constituting playing divisions. The playing divisions are colored alike and the playing divisions of each row are spaces differently colored from the other 65 spaces of the row. The playing field consists of nine rows of eight playing divisions. The playing divisions are designated consecutively from 1 to 72.

The game apparatus includes two sets of 70 playing pieces or members and each set includes twenty-four pieces or members. By way of example, a player piece or member is illustrated in Fig. 2, and is designated by the reference character B. As illustrated 75 the player piece B is in the form of an equilateral triangular-shaped block, but it is obvious that the player piece can be of any suitable form.

The game apparatus further includes two 80 triangular-shaped blocks indicated by the reference character a and each of which represents a fort or is suitably designated as a fort and one of said blocks is positioned upon the space b exteriorly of the playing 85 field. A fort associates with a set of playing pieces or members.

The game apparatus further includes six 90 triangular-shaped blocks designated by the reference characters d, e, f, g, h, i, the blocks d, e, f, g have the representation of a wireless telegraph station or are designated as such. The block e is positioned upon the space j, the block d upon the space k, the block f upon the space l, and the block g 95 upon the space m. The spaces j and m are exterior of the playing field. The blocks d and e associate with one set of playing members of pieces while the blocks f, g, associate with the other set of playing pieces or members. The block h is the representation of a wireless torpedo station or is designated as such and said block h is positioned upon the space n, and the block i is the representation of a wireless torpedo station or des- 100 105 ignated as such and is positioned upon the space o. The spaces n and o are exterior of the playing field. The block h associates

with one set of playing members or pieces while the block *i* associates with the other set.

- 5 Each of the pieces of each set of playing pieces or members is the representation of an object, or is designated as such object, each set of pieces are represented to be aerial, marine and sub-marine vessels and mines or are designed as such and for each 10 set of playing pieces there are three aero-mine scouts, designated by the reference character C; three sub-marine mine scouts, indicated by the reference character D, one aeromine indicated at E; one wireless aero- 15 mine indicated at F; one dreadnaught indicated at H; one gunboat indicated at G; one observation mine indicated at K; one wireless sub-marine boat indicated at L; one sub-marine torpedo boat indicated at I; 20 one electro-contact mine indicated at J; one torpedo destroyer indicated at M; one gunboat indicated at N; one aerial torpedo ship indicated at O; one armored cruiser indicated at P; one turret battleship indicated at Q; one flagship indicated at R; 25 one hydro-aerial warship indicated at S; one protected cruiser indicated at U; one aerial destroyer indicated at T and one super dreadnaught indicated at V.
- 30 The representation of two pairs of shore batteries are provided at W, and each battery has an indicator Z associated therewith. The indicators are in the form of oblong strips and when placed upon a battery, it 35 indicates that the battery has not been silenced, but when removed, that the battery has been silenced.
- 35 The playing piece of each set which represents the flag-ship is the objective piece to 40 be captured.
- 40 The pieces of one set are positioned when starting the game upon the following playing division, the pieces C upon the divisions 18, 22 and 24; the pieces D upon divisions 45 17, 20 and 23; the piece E upon the division 19; the piece F upon the division 21; the piece G upon the division 9; the piece M upon the division 15; the piece L upon the division 14; the piece K upon the division 50 13; the piece J upon the division 12; the piece I upon the division 11; the piece H upon the division 10; the piece N upon the division 16; the piece O upon the division 1; the piece U upon the division 2; the piece 55 Q upon the division 3; the piece R upon the division 4; the piece S upon the division 5; the piece T upon the division 6; the piece P upon the division 7; the piece V upon the division 8.
- 60 The pieces of the other set when positioned for the game are placed upon the following playing division:—the piece V upon the division 72; the piece U upon the space 71; the piece T upon the division 70; the piece 65 S upon the division 69; the piece R upon the

division 68; the piece Q upon the division 67; the piece P upon the division 66; the piece O upon the division 65; the piece N upon the division 64; the piece M upon the division 63; the piece L upon the division 62; the piece K upon the division 61; the piece J in the division 60; the piece I in the division 59; the piece H in the division 58; the piece G in the division 57; the piece C in the division 56; the piece E in the division 51; the pieces D in the divisions 55, 52, 49; and the piece F in the division 53. The indicators Z are positioned as shown upon the shore batteries.

When the pieces of each set are positioned in the foregoing manner for the starting of the game, the blocks *a*, *b*, *d*, *e*, *f*, *g*, *h*, *i*, are arranged in the manner as hereinafter referred to and when the wireless stations are out of commission or the fort silenced, the blocks are removed, that is to say, if a wireless station is out of commission it is removed, or when a fort is out of commission it is removed.

The pieces of one set take a piece of another set somewhat along the lines of chess. Between the sets of playing pieces when positioned to start the game, three rows of playing divisions are arranged.

The manner in which the playing pieces of each set move is as follows:—The playing pieces G and V both move either transversely or horizontally of the playing field and over any desired number of vacant playing divisions. The playing pieces P and U move diagonally at an angle of 60° over any number of unoccupied playing divisions. Playing piece P moves to the right, the playing piece U to the left. Both move one division in a diagonal direction opposite to their direction of movement as first stated. The playing pieces O, S and T move one playing division diagonally at an angle of 30°, then one at an obtuse angle of 150°. Playing piece S has in addition a similar move horizontally. Playing pieces O, S and T are placed on playing divisions so that no matter how moved in the manner assigned to them, they never meet on the same playing division. Playing pieces N and G move one playing division diagonally at an angle of 60° to the left or right. Playing pieces M, I and Q move diagonally at an angle of 30° over to the left or right over any number of unoccupied playing divisions. The playing piece I can move as under the playing piece on the first playing division in the path of its movement, if said playing division be occupied. Playing piece Q moves also one playing division horizontally. Playing pieces M, I and Q are placed on playing divisions so that, in their assigned move they never come on the same division. Playing piece L moves two or three playing divisions diagonally in either direction, the

move being as under the playing pieces in the adjacent playing divisions. The movement of the playing piece J is limited to the fifth row of playing divisions from the shore and its movement is dependent upon one wireless station. The playing piece is destroyed when both wireless stations are destroyed. The move is to indicate traveling under a playing piece on an adjacent division to blow another piece up. Playing piece R which is the objective piece attacked or protected by the defense moves on adjacent playing divisions of one color and can also move on the other triangular division of a different color. For example if the playing field is divided into black and white, the playing piece R moves an adjacent division whether black or white, but limited to one division in its movement. The playing piece R is limited in its movement to the black playing divisions when one mine is left and it takes any playing piece on an adjacent playing division. Playing pieces C and D move one division forward at a time diagonally. To avoid a playing piece or a playing division within range of the coast defenses, they may move as over and under an adjacent playing division diagonally or transversely, but take one division diagonally only. Playing piece C can counter-mine aerial mines only. Playing piece D can counter-mine floating or submarine mines only. Pieces C and D when reaching first row of playing divisions can move transversely one playing division. The shore batteries have a range of two playing divisions in a horizontal direction to destroy, when their associated pieces do not intervene. The forts have a range of two playing divisions forward diagonally to destroy when their associated pieces do not intervene. The wireless torpedo has a range of two playing divisions at an angle of 30° and two horizontally to destroy when their associated pieces do not intervene. Playing pieces F, E, K and J representing mines do not move. The playing piece which represents the wireless aeromine is dependent upon the two wireless stations and is put out of commission if one wireless station is destroyed. The piece registering the aeromine is independent of wireless stations, but under control. The wireless aeromine and aeromine can destroy aerial craft only. Said aerial craft cannot pass over a playing division occupied by an aerial mine. The sub-marine mines are controlled from shore and are destroyed by sub-marine scouts only, unless the player wishes to fire a mine when the enemy's ship passes over. The mines can be fired but once, but the player fires only when he considers passing ship of more value than mine. Marine and sub-marine craft cannot pass over the playing divisions occupied by the sub-marine mines. Coast defenses and

wireless stations can be destroyed by aerial, marine, or sub-marine craft. Any playing piece in its assigned move can take any coast defense piece if it is positioned outside of the range of the defense piece when no pieces are interposed in the path of movement of the playing piece.

What I claim is:—

1. A game apparatus comprising a playing field having seventy-two playing divisions arranged in rows, two sets of playing pieces, each set consisting of twenty-four and the pieces of each set representing aerial, marine and sub-marine vessels and mines.

2. A game apparatus comprising a playing field formed of rows of similar playing divisions, two sets of playing pieces of equal numbers associated with said playing fields and each set representing aerial, marine and sub-marine vessels and mines, said playing field having associated therewith the representations of shore batteries, blocks representing forts and wireless stations, and indicators associated with said batteries.

3. A game apparatus comprising a playing field having seventy-two playing divisions arranged in rows, two sets of playing pieces, each set consisting of twenty-four and the pieces of each set representing aerial, marine and sub-marine vessels and mines, said playing field having associated therewith the representation of shore batteries, wireless stations and forts, and indicators associated with said forts, wireless stations and shore batteries.

4. A game apparatus comprising a playing field divided into rows of triangular spaces numbering seventy-two, the spaces of each row being alternately colored dividing said spaces into playing divisions, the playing divisions of each row being differently colored from the other spaces of the row and two sets of playing pieces associated with said field, each set including twenty-four pieces, the pieces of each set representing aerial, marine and sub-marine vessels and mines, said playing field having associated therewith the representation of shore batteries, blocks representing forts and wireless stations, and indicators associating with said shore batteries.

5. A game apparatus comprising a playing field formed of seventy-two triangular playing divisions and two sets of playing pieces associated with said field, each set consisting of twenty-four members.

6. A game apparatus comprising a playing field divided into rows of sixteen triangular spaces, the spaces of each row being divided into eight playing divisions, and two sets of playing pieces associated with said field, each set consisting of twenty-four elements.

7. A game apparatus comprising a playing field, playing elements associated there-

with and representing war crafts, two sets of stationary elements associated with said field and representing coast defenses and two other sets of stationary elements associated with the field and representing wireless stations.

8. A game apparatus comprising a playing field formed of seventy-two triangular spaces arranged in rows of sixteen, each row divided into eight playing divisions and playing elements associated with said field.

9. A game apparatus comprising a rectangular field having inner and outer rows of playing divisions and two sets of playing elements, each set including a plurality of movable members shiftable upon all of said playing divisions and a plurality of stationary members normally mounted within the field upon the inner row of playing divisions.

10. A game apparatus comprising a rectangular field having inner and outer rows of playing divisions and two sets of playing elements, each set including a plurality of movable members shiftable upon all of said playing divisions, and further including a plurality of stationary members, some of said stationary members being normally mounted within the field upon the inner row of playing divisions, and the remainder of said stationary members normally mounted upon said field exteriorly of said rows of inner and outer divisions.

11. A game apparatus comprising a rectangular field having rows of playing divisions and two sets of playing elements

associated with said rows of playing divisions, each set including 20 movable and 4 stationary members.

12. A game apparatus comprising a rectangular field having rows of playing divisions, and two sets of playing elements associated with said field and divisions, each set including a plurality of members, shiftable upon all of said divisions, and each set further including a plurality of stationary members, certain of which are normally mounted upon certain of the playing divisions and the other of which is normally mounted upon said field exteriorly of said playing divisions.

13. A marine war game apparatus comprising a field having rows of playing divisions, playing members provided with conventional indications to constitute forts, wireless torpedo stations, and wireless stations, said members arranged exteriorly of said rows of playing divisions, shiftable playing members movable over all of said playing divisions and provided with conventional means to constitute marine and submarine war craft, and stationary playing members normally mounted upon certain of said playing divisions and provided with conventional means to constitute mines.

In testimony whereof I affix my signature in the presence of two witnesses.
